BOTTLE

Yasuyuki Sawachi, Tokyo-to, Japan, assignor to Kabushiki Kaisha Shiseido (also trading as Shiseido Co., Ltd.),
Tokyo-to, Japan

Filed Jan. 25, 1966, Ser. No. 762

Term of patent 14 years

(Cl. D58—6)

FIG. 2

FIG. 1

FIG. 4

FIG. 5

FIG. 6

FIG. 1 is a front elevational view of a bottle, showing my new design.

FIG. 2 is a top plan view thereof.

FIG. 3 is a bottom plan view thereof.

FIG. 4 is a side elevational view thereof, the opposite side being the same in appearance.

FIG. 5 is a rear elevational view thereof, and

FIG. 6 is a perspective view thereof with the cap removed.

I claim:

The ornamental design for a bottle, as shown and described.
